The ornamental design for a display screen with transitional graphical user interface, as shown and described.

DESCRIPTION

FIG. 1 is the first image in a sequence for a display screen with transitional graphical user interface showing my new design on a device;

FIG. 2 is the second image thereof;

FIG. 3 is an enlarged partial view of the first image of the display screen with transitional graphical user interface; and, FIG. 4 is an enlarged partial view of the second image. The appearance of the transitional graphical user interface sequentially transitions between the images shown in FIGS. 1-2 and FIGS. 3-4. The process or period in which one image transitions to another forms no part of the claimed design. In the drawings, the broken lines are for the purpose of illustrating portions of a display screen with transitional graphical user interface and environmental structure that form no part of the claimed design.
